UNITED STATES PATENT OFFICE.

PAUL FRED HAASE, OF KANSAS CITY, MISSOURI.

SQUARE-RULE.

1,098,571.

Specification of Letters Patent. Patented June 2, 1914.

Application filed August 19, 1912. Serial No. 715,925.

To all whom it may concern:

Be it known that I, PAUL FRED HAASE, of 1125 Paseo, Kansas City, in the county of Jackson and the State of Missouri, have invented a new and useful Device to be Known as a Square-Rule; and I do hereby declare that the following is a full, clear, and exact description of the same, reference being had to the accompanying drawings, forming part 10 thereof.

My invention relates to folding rules, and has for its principal object to provide a device of that type which is adapted for use as either a straight edge or a square.

In a general way, the invention consists of providing a rule of the ordinary jointed type with a special joint, the adjacent end portions of which are beveled so that when one of the specially jointed sections is turned past center it will coöperate with its mating section to form a right angle or square rule, the invention consisting more particularly in the detailed construction of the joint whereby the square forming sections are connected.

The preferred form and construction of the rule, and the novel construction of the joint, are illustrated in the accompanying drawings, wherein,

Figure I is a perspective view of a square rule constructed according to my invention, showing the parts in condensed arrangement. Fig. II is a perspective view of the rule, showing the sections partly spread. Fig. III is an elevation of the rule, showing the sections arranged to form a square. Fig. IV is an edge view of the square joint. Fig. V is a detail view of the square joint parts, showing their relation when the rule is in 40 the position illustrated in Fig. I.

Referring more in detail to the parts: 1 designates the rule sections, each of which is constructed in the ordinary manner, except for the improvements hereinafter mentioned, the body of the sections being usually formed of wood and marked off for inches and fractions of inches, and the better constructions being provided with metal edge strips and tips.

One of the inner sections 2 of the rule is rabbeded at its outer end and carries hinge plates 3, the outer faces of which lie in the same plane as the faces in the rule section and bear the inch graduations for that part 55 of the section which they cover, the ends of the hinge plates being extended beyond the

ends of the rule section and provided with disks 4 which are offset from one edge in order to properly mount the mating hinge parts as will presently be described, and the opposite edge of the plate being beveled, as shown at 5. The end of the rule section 2 contained between the plates 3 is cupped, as shown in dotted lines, Fig. 1, to provide a pocket within which the hinge member of the adjacent section may rotate.

On the end section 6, which is adapted for coöperation with the section 2 to form the square, are plates 7 which are also countersunk into the sides of the rule section, as are the plates 3 on the section 2, and bear the inch graduations for the parts of that rule section which they cover. The section 6, however, does not extend the full length of the hinge plates, but terminates a short distance from the outer ends thereof to leave a socket between the projecting ends of the plates into which the inner ends of the inserts 10 may project. The plates 7 have no disks corresponding with the disks 4 of sections 3, their end portions being shaped to provide the sockets 9 which are adapted for receiving the edges of the disks 4 when the parts are assembled.

The hinge members on the end rule section 6 comprise inserts 10, the heads 11 of which are contained between and riveted to the projecting ends of the plates 7 and abut against the ends of the body of section 6, each head having a disk 12 thereon of the same diameter, and corresponding to the disks 4 on sections 3, the disks being offset similarly but oppositely to the first disks 4, and the edges of the head 11 being beveled at 13 to correspond with the bevel of the hinge plates 3 on the section 2, so that when the beveled edges abut the rule sections will form a true square, as illustrated in Fig. III.

With the hinge members on the section 6 formed separately as described, with the disk heads contained between the plates 7, the disks 12 may be contained between the disks 4, so that when a pin 14 is extended therethrough the parts may pivot relatively to each other, as with any of the other hinges, the only difference being that by offsetting the disks, and beveling the parts, at the ends of the separate rule sections, the end sections may turn past a center and to a right angle with the section 2, so that the rule may be used as a square when so arranged. It is apparent that with this con-

struction, all of the parts are of the same thickness so that there are no projecting edges from either the bodies of the rule section or from the hinge parts.

3 Having thus described my invention, what I claim as new therein, and desire to secure by Letters-Patent, is:—

10 The combination with two rule sections, of plates fixed to opposite sides and projecting from the end of one of said sections, the projecting ends of said plates being beveled at one edge and provided with apertured disk portions, plates fixed to and projecting from the end of the second rule section,

hinge members located between the projecting ends of said last named plates and having disks contained by and pivotally connected with the disk portions of the plates on the first section, the ends of the plates and the contained portions of the hinge members of the second section being beveled to coöperate with the beveled parts of the first section to form a square, substantially as set forth.

PAUL FRED HAASE.
